CLAIM

The ornamental design for an electrical connector for a merchandise security system, as shown and described.

DESCRIPTION

FIG. 1 is a perspective view of an electrical connector for merchandise security system showing my new design;

FIG. 2 is a front elevational view thereof, the rear view being plain and unornamented;

FIG. 3 is a front elevational view thereof; and

FIG. 4 is a side elevational view thereof.

The broken line showing of the connector is for illustrative purposes only and forms no part of the claimed design.

FIG. 1

FIG. 2

FIG. 3

FIG. 4
